UNITED STATES PATENT OFFICE.

ALFRED E. MEGERLIN, OF NEW YORK, N. Y.

TOY.

1,370,337.

Specification of Letters Patent.

Patented Mar. 1, 1921.

Application filed May 8, 1920. Serial No. 379,958.

To all whom it may concern:

Be it known that I, ALFRED E. MEGERLIN, a citizen of Belgium, residing at New York, in the county of New York and State of New York, have invented new and useful Improvements in Toys, of which the following is a specification.

This invention relates to a toy which may be used as a wind vane and the principal object of the invention is to provide a wheel, adapted to be driven by the wind and two figures, representing men, operating as a cross cut saw and means for reciprocating the saw and causing the figures to bend by the rotation of said wheel.

Another object of the invention is to so pivot the device on an upright or the like so that the part carrying the figures and saw will act as a vane for keeping the wheel in the wind.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a side view of the device.

Fig. 2 is a plan view thereof.

Fig. 3 is a bottom plan view of the vane part.

Figs. 4 and 5 are enlarged views showing the means for slidably supporting the saw.

In these drawings 1 represents a platform which is pivoted to the supporting post 2 by the pin 3, said pin being located adjacent one end of the platform. This end of the platform carries the bearing blocks 4 in which the shaft 5 is mounted. The wind wheel 6 is connected with the outer end of the shaft while the inner end of the shaft carries the bevel gear 7. A bracket 8 is connected with one of the blocks 4 and this bracket supports the crank shaft 9 which passes through an opening in the platform and has its crank arranged below said platform. The upper end of this shaft carries the bevel gear 10 which meshes with the gear 7. A pair of figures 11, representing men, are carried by the platform, the arms and legs of the figures being pivoted to the bodies

thereof. The arms of said figures are pivoted to the handles 12 of a cross cut saw 13 which is slidably supported on the platform, between the figures, by means of the upright pieces 14, on each side of the platform which are connected together by the pins 15, said pins passing through the slot 16 in the saw. A slot 17 is formed in the platform under the saw 13 and an L-shaped rod has one limb 65 passing through said slot and formed with the saw. The other limb passes through the guides 19 supported from the platform and this limb is connected with the crank by the link 20.

It will thus be seen that the rotation of the wind wheel will cause the crank shaft to revolve and thus reciprocate the rod 18 and as the vertical part of this rod is connected with the saw, said saw will be reciprocated and this movement of the saw will cause the figures to alternately bend and assume an upright position as if they were actuating the saw. It will also be seen that said figures and saw will be acted upon by the wind so as to make this part of the device act as a vane to keep the wheel in the wind.

The device can be used as a toy to amuse a child by operating the wheel by hand to actuate the figures or the device may be used as a wind vane or as an ornament for an automobile or other vehicle.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising a platform, an upright, means for pivotally connecting a part of the platform, adjacent one end thereof, to the upright, a shaft rotatably carried by the platform, a wind wheel on said shaft, a crank shaft carried by the platform geared to the first mentioned shaft, a saw slidably supported upon the platform, means for connecting the saw to the crank shaft so that the rotation of the shaft will reciprocate the saw and a pair of figures, representing men, supported from the platform and having their arms and legs pivotally connected with the trunks and the arms pivotally connected with the handles of the saw.

2. A device of the class described comprising a platform, an upright on which the platform is pivotally supported, a shaft journaled on the platform, a wind wheel connected with one end of the shaft, figures supported on the platform and representing men in the act of sawing and means for

moving the figures by the rotation of the wind wheel, said wheel being arranged at one end of the platform and the figures at the other end so that said figures will act as a vane for keeping the wheel in the wind.

In testimony whereof I affix my signature.

ALFRED E. MEGERLIN.
